UNITED STATES PATENT OFFICE.

HENRY H. YERK AND WILLIAM J. BAUMBERGER, OF DAVENPORT, IOWA, ASSIGNEES
TO MICRO MACHINE COMPANY, OF BETTENDORF, IOWA, A CORPORATION OF IOWA.

COLLAPSIBLE BOX.

Application filed March 3, 1924. Serial No. 696,435.

This invention relates to folding boxes or crates particularly useful for shipping articles such as bread, etc., and is designed to be folded into compact form for return shipment.

An object of the present invention is to provide a folding box which can be very quickly and easily folded into a compact form in which the parts of the box are so nested together that they are effectively protected against injury by rough handling in the return shipment.

A further object of the invention is to provide locking means in connection with the hinged lid of the box which serves to hold the lid in closed position when the box is in use and which also serves to lock the box in collapsed condition.

A further object is to provide a folding box having a hinged lid which is adapted when opened to hang vertically at the rear side of the box.

A further object is to provide, in connection with a folding box having collapsible end walls, means for stiffening and rigidly securing the end walls in extended position.

A further object is to provide a folding box whose top and bottom, side and end walls are formed of sheet metal sections hingedly connected by hinge members so constructed and positioned as to effectively reinforce the structure.

With the above and other objects in view the invention may be said to comprise the structure illustrated in the accompanying drawings, described in the following specification and particularly set forth in the appended claims, together with such variations and modifications thereof as will be apparent to those skilled in the art to which the invention appertains.

Reference should be had to the accompanying drawings forming a part of this specification, in which—

45. Figure 1 is a top plan view of a folding box embodying the invention, the upper portion of the box being broken away at one end to show a portion of the bottom in elevation and the walls in horizontal section.

50. Fig. 2 is a view taken as indicated by the line 2—2, Fig. 1, showing one half of the box in front elevation and the remainder in vertical section.

55. Fig. 3 is a transverse, vertical section taken on line 3—3, Fig. 2.

Fig. 4 is a horizontal section taken on the line 4—4, Fig. 2, and showing the box partially collapsed.

Fig. 5 is a horizontal section through the box when collapsed.

Fig. 6 is an enlarged vertical section taken on line 6—6, Fig. 5.

Fig. 7 is a detail view showing the hinge connection between the lid and upper flange of the rear wall of the box.

Fig. 8 is a vertical section through a lower end corner of the box taken on line 8—8, Fig. 1.

Fig. 9 is a vertical section taken on line 9—9, Fig. 8.

Fig. 10 is a perspective view of a box of substantially the same construction as that illustrated in Figs. 1 to 9 but having a lid of somewhat different construction.

Fig. 11 is a sectional view taken on line 11—11, Fig. 10.

Referring to the drawings, the box consists of a rear wall 1 formed of a single piece of sheet metal, a front wall 2 also formed of a single piece of sheet metal, end walls formed of sections 3, 4 and 3', 4', hinged together and to the rear and front walls to fold inwardly, a lid 5 hinged to the rear wall 1, and a bottom formed by a section 6 hinged to the rear wall 1 and a section 7 hinged to the front wall. As shown in Figs. 5 and 6, the section 6 of the bottom folds into upright position between the rear wall 1 and the sections 3, 3' of the end walls, the section 7 of the bottom folds into upright position between the front wall 2 and the sections 4, 4' of the end walls, and the lid 5 folds over the outside of the front wall 2. The wall, lid and bottom members are all formed of sheet metal with panels stamped therein to provide the necessary rigidity.

The rear wall 1 has its ends bent inwardly at right angles to form flanges 8, its lower edges bent inwardly to form a bottom flange 9, and its upper edge bent inwardly to form a top flange 10, the flange 10 extending inwardly farther than the flanges 8 and 9 for a purpose which will presently appear.

The front wall 2 is also provided with marginal inturned flanges, 11 at the ends thereof, 12 at the bottom thereof and 13 at the top thereof. The sections 3, 3' of the end walls are hinged along their rear edges to the inwardly extending flanges 8 of

60

105

110

the rear wall, the edges of the flanges 8 and the sections 3 being cut away and turned back upon themselves to provide interfitting hinge knuckles which are joined by means of hinge pintles 14 extending the full length of the section. The sections 4, 4' of the end walls are joined to the flanges 11 of the front wall by means of pintles 15 in exactly the same way as the sections 3 are joined to the flanges 8 of the rear wall. The end sections 3 and 4 are formed to provide interfitting hinge knuckles at their inner edges and are joined by pintles 16 which extend the full length thereof. One section of each of the end walls has a stop plate 17 secured to the inner edges thereof upon the inside, which, when the sections have been extended into alignment with each other, engage the inner sides of the sections 4 of the end wall and prevent further outward movement.

Upon the upper edges of each of the end sections 4, 4', are mounted bridge members 4^a, 4^b which conform to the roll top edges of these sections and are adapted to be slid along them to engage the sections 3, 3' when they are alined respectively with the sections 4, 4'; that is, when the box is in open position. The members 4^a, 4^b therefore serve to hold the upper parts of the end sections 3, 4 and 3', 4' rigidly together against swinging inwardly about the hinge pinte 16. In order to limit the sliding movement of the members 4^a, 4^b rearwardly along the top edges of the sections 4, 4', lugs 4^c are provided which project downwardly and engage the hinges 16 and thus stop further rearward movement. Of course when it is desired to collapse the box the members 4^a, 4^b are moved so that they are disposed entirely on the sections 4, 4' and do not engage the sections 3, 3'.

The front wall 2 is of the same length as the rear wall 1 but the height of the front and end walls is slightly less than the rear wall so that in folding the front and end walls may move freely into positions beneath the top flange 10 of the rear wall with their upper edges closely adjacent thereto, as shown in Fig. 6.

The edge of the top flange 10 of the rear wall and the rear edge of the lid are formed into hinge knuckles which interfit and the lid 5 is connected to the flange 10 by a hinge pinte 18 extending the full length of the box. The front and end edges of the lid 5 are formed with downturned flanges 19 adapted to fit over the front and end walls of the box when the box is extended.

At the free forward edge of the lid 5 and substantially midway between the ends thereof there is a transversely extending latch bar 20 (see Figs. 1 and 2) which is slidably mounted upon the under side of the lid within a raised portion 21 projecting

from the raised panel 22 stamped in the lid, the outer end of the bar 20 projecting through the downturned flange 19 of the lid. The bar 20 is pressed outwardly by means of a spring 23 and has a downwardly and outwardly bent retaining lug 24 secured to its under side and adapted to engage beneath the inturned upper flange 13 of the front wall to retain the lid in closed position. The portion of the latch bar 20 which projects through the flange 19 of the lid is provided with an aperture 25 adapted to receive a padlock or other device for locking the latch bar in lid locking position with the lug 24 thereof beneath the flange 13.

The rear edge of the section 6 of the bottom is formed to provide hinge knuckles which interfit with hinge knuckles formed on an angle strip 26 extending the full length of the rear wall a short distance above the bottom thereof and is joined thereto by means of a hinge pinte 27 extending the full length of the section 6. The hinge connection between the rear wall 1 and bottom section 6 is closely adjacent the wall 1 so that the bottom member 6 may be folded up flat against the rear wall 1 to permit the inwardly folding sections 3, 3' and 4, 4', of the end walls to fold together at the front thereof.

The forward edge of the section 7 of the bottom is hinged at 28 with annular knuckles formed on a strip 28' secured to the front wall 2 slightly above the bottom thereof and is joined to said strip by a hinge. The hinge connection between the bottom section 7 and the front wall 2 is closely adjacent the wall, permitting the section 7 to be folded up against the section 2 within the end flanges 11 thereof so that the section 7 lies between the front wall 2 and the folded sections 4, 4' of the end walls when the box is folded.

The end sections 3, 3' and 4, 4' have upwardly facing channel members 29 (see Fig. 8) secured upon their inner sides along their lower edges and the bottom sections 6 and 7 are provided with strips having downturned end flanges 30 which engage in the channel members 29 when the walls of the box are extended and the bottom members are swung down to horizontal position, the channel members 29 serving to reinforce the bottom edges of the sections of the end walls and also as supporting members for the hinged members 6 and 7 forming the bottom of the box. The free edge of the forward section 7 of the bottom rests upon the free edge of the section 6 and is locked against upward movement by a pivoted latch member 31 carried by the section 6 midway between its ends and adapted to be turned into a position overlying the edge of the section 7.

In order to hold the bottom of the box

rigidly in place and to reinforce the ends of the box along the bottom; means is provided for securely fastening the end edges of the bottom sections to the channel members 29. To this end the inner flanges of the channels 29 are provided with integral tongues 32 projecting upwardly at intervals from its upper edge. These tongues extend through slots 33 in the bottom sections and are provided with elongated openings 34 which are adapted to receive projections 35 extending outwardly from the side edges of flat bars 36 connected at one end by a pivot 37 to the section 6 of the bottom adjacent the ends thereof and close to the hinge connection between the section 6 and rear wall 1. The bars 36 lie flat against the bottom section 6 and are adapted to be positioned alongside of an in contact with the upwardly projecting tongues 32 of the channel members 29 with the projections 35 extending through the openings 34 in the tongues 32 and through slots 38 in the flanges of the channel members 29. The bars 36 extend substantially the full length of the end walls and are adapted to be swung inwardly clear of the channel members 29 and the bottom section 7, as shown in dotted lines in Fig. 1, to permit the bottom members to be folded up against the rear and front walls. A stop member in the form of a clip 39 is secured to the central portion of the bottom section 6 and serves to hold the bars in diagonally disposed depressions 40 between the raised portions 41 formed in the bottom section 6 so that the bars do not interfere with the folding of the section 6 against the rear wall 1. The outer ends of the bars 36 are provided with hinged spring clips 42 which are adapted to be swung down to resiliently press against and releasably engage both sides of the forward tongues 32 of the channels 29 carried by the sections 4, 4' and 3, 3' of the end walls, to retain the bars 36 in locking position.

Centrally of the rear wall 1 there is a forwardly projecting horizontal bracket 44 which underlies the section 6 of the bottom of the box and extends, when the box is folded as shown in Figs. 5 and 6, through a horizontal slot 45 in the front wall 2. The length of the bracket 44 is such that when the box is folded the forward edge thereof will be engaged by the lid 5 hanging in vertical position; and adjacent its forward edge the bracket is provided with a slot 46 adapted to receive the retaining lug 24 of the spring-pressed latch bar 20 carried by the lid 5. By locking a padlock upon the end of the latch bar 20, the bar will be held against releasing movement and the box may thus be locked in collapsed condition.

Supporting members for the box are provided in the form of corner clips 47 secured to the bottom corners of the flanged front

and rear walls 1 and 2, and suitable flexible supporting handles 48 may be secured to the ends of the box.

In Figs. 10 and 11 of the drawing there is shown a folding box constructed in substantially the same manner as the box above described except that a modified form of hinged lid is employed. In this modification the lid 5^a is connected to the forward flange 10^a of the rear wall by means of a narrow intermediate section 49 hinged to the flange 10^a and to the body portion of the lid. This narrow section 49 is of a width substantially equal to the width of the flange 10^a so that when the lid is swung rearwardly the strip 49 overlies the flange 10^a so that the body 5^a of the lid can swing down to vertical position back of the rear wall of the box, thus positioning the lid out of the way when opened.

As shown in Figs. 7 and 11, the forwardly extending flanges 10 and 10^a, respectively, of the rear sections are formed of double thickness to produce strong hinge knuckles 50. This is accomplished by utilizing a blank having a sufficient length so that it may be folded back upon itself to form the rolled hinge and this extra portion is preferably of such a length that it reinforces the corner and extends part of the way down the back section 1. It will also be noticed that bracing members 51 are formed integrally with the flange 10 of the back and these bracing members extend across the flanges 8 and around to the rear wall itself. Furthermore, it is to be understood that the particular forms of apparatus shown and described, and the particular procedure set forth, are presented for purposes of explanation and illustration and that various modifications of said apparatus and procedure can be made without departing from our invention as defined in the appended claims.

What we claim is:

1. A folding box comprising front and rear walls, end walls each comprising a pair of sections hinged together and to the front and rear walls and disposed inwardly between the front and rear walls, a bottom member hinged to one of the side walls and swinging upwardly, and bridging members carried by certain of said end wall sections, said members being slidable to rigidly interlock with the adjacent end wall sections to hold them against inward swinging movement.

2. A folding box comprising front and rear walls, end walls each comprising a pair of sections hinged together and to the front and rear walls and disposed inwardly between the front and rear walls, a bottom member hinged to one of the side walls and swinging upwardly, said bottom member and end wall sections having engaging means to

85

90

95

100

105

110

115

120

125

130

prevent inward swinging movement of the end wall sections at their lower edges, and means provided at the top of said end wall sections, said means being movable to bridge 5 said sections and lock them against inward swinging movement.

3. A folding box comprising a pair of side walls, end walls consisting of sections hinged together and to the ends of the side walls to fold inwardly between the side walls, upwardly facing channels along the bottom edges of the sections of the end walls, a bottom member hinged to one of the side walls, said member having edge flanges 15 adapted to fit in said channels, and means for locking said bottom member to the end walls with the flanges engaging in the channels.

4. A folding box comprising a pair of side walls, end walls consisting of sections hinged to each other and to the ends of the side walls to fold inwardly between the side walls, upwardly extending tongues carried by the end wall sections adjacent the bottoms thereof 25 of, a bottom member hinged to a side wall, said bottom member having openings to receive said tongues, and means carried by the bottom member and adapted to be moved into locking engagement with said tongues.

30 5. A folding box comprising a pair of side walls, end walls consisting of sections hinged to each other and to the ends of the side walls to fold inwardly between the side walls, upwardly facing channels along the lower edges of the sections of the end walls, the inner flanges of the channels having tongues projecting upwardly therefrom, a bottom member hinged to a side wall and having edge flanges adapted to engage in 35 said channels and having openings to receive the tongues, and bars pivoted to said bottom member and adapted to be moved into interlocking engagement with said tongues.

6. A folding box comprising a pair of side walls, end walls consisting of sections hinged together and to the ends of the side walls to fold inwardly between the side walls, supporting members adjacent the bottoms of said sections having upwardly extending 45 tongues, said tongues having slots therein, a bottom member hinged to one of the side walls, said bottom member having openings to receive said tongues, a bar hinged adjacent each end of the bottom member, said 50 bar having spaced lugs adapted to engage in the slots of the tongues.

7. A folding box comprising a pair of side walls, end wall and bottom sections adapted to be folded between the side walls, 60 a lid hinged to one of the side walls and adapted to overlie the opposite side wall when the box is folded, locking means carried by the lid adapted to engage with the opposite side wall when the box is extended, 65 and means carried by the first-mentioned

side wall at the bottom thereof adapted to be engaged by the locking means when the box is folded.

8. A folding box comprising front and rear walls having inwardly extending flanges 70 along the upper and side edges thereof, end walls, each consisting of sections hinged together and to the inturned end flanges of the front and rear walls, a lid hinged to the top flange of the rear wall, said lid being adapted to hang vertically over the front wall when the box is folded, a latch carried by the lid and adapted to engage beneath the top flange of the front wall when the box is extended, and a forwardly 75 extending bracket carried by the rear wall at the bottom thereof, said bracket having a slot adapted to receive the latch of the lid when the box is folded.

9. A folding box comprising front and 80 rear walls having inturned edge flanges at the top, bottom and ends, hinged members forming the end walls and bottom of the box and adapted to be folded between the front and rear walls thereof, and reinforcing 85 and supporting clips secured to the bottom corners of the front and rear walls.

10. In folding box, the combination with a rear wall having a forwardly extending flange at the top thereof, of a front wall, 90 end walls and a bottom, all adapted to be folded together upon the rear wall beneath the top flange thereof, and a lid hinged to the top flange of the rear wall, said lid having downturned edge flanges adapted to fit 95 over the upper edges of the front and end walls.

11. In a folding box, the combination with a rear wall having a forwardly extending flange at the top thereof, of a front wall, 100 end walls and a bottom, all adapted to be folded together upon the rear wall and beneath the top flange thereof, and a lid hinged to said flange and adapted to cover the top of the box when the box is extended 105 and to overlie the front wall when the box is folded, said lid consisting of inner and outer hinged connected sections, the inner section being of substantially the same width as said forwardly extending flange so that 110 when the lid is opened the outer section thereof may hang vertically immediately behind the rear wall.

12. In a folding box, the combination with a rear wall having a forwardly extending 115 flange at the top thereof, of a front wall, end walls and a bottom, all adapted to be folded together upon the rear wall beneath the top flange thereof, and a lid hinged to the top flange of the rear wall, said lid and 120 said top flange having metal portions folded back upon themselves to form hinge knuckles of both members of double thickness.

13. The invention specified in claim 12 in which the folded back portion of the top 125

flange of the rear wall extends to underlie and reinforce the upper rear corner and upper portion of the rear wall.

14. In a folding box, the combination with
5 a rear wall having a forwardly extending flange at the top thereof and end flanges at the sides thereof, of a front wall, end walls and a bottom, all adapted to be folded together upon the rear wall beneath the top

flange thereof, and a lid hinged to the top 10 flange of the rear wall, said top flange having corner bridge members integrally formed therewith which overlie and reinforce said end flanges.

In testimony whereof, we hereunto affix 15 our signatures.

HENRY H. YERK.

WILLIAM J. BAUMBERGER.
